UNITED STATES PATENT OFFICE.

EDWARD FOSTER CLARK, OF NORTH ATTLEBORO, MASSACHUSETTS, ASSIGNOR TO W. G. CLARK & CO., (INC.), OF NORTH ATTLEBORO, MASSACHUSETTS, A CORPORATION OF MASSACHUSETTS.

POCKET CIGAR LIGHTER.

Application filed March 23, 1926. Serial No. 96,858.

My invention is a flint-spark cigar lighter and resides in the details of organization and arrangement of the various elements going to make up a practical and efficient device of this character, giving certainty of action, cleanliness of operation and security against leakage or evaporation of the liquid fuel.

In the drawings:—

Figure 1 is a side elevation of the complete device, partly broken away;

Figure 2 is an elevation of the opposite side of the device;

Figure 3 is a plan view of Figure 2;

Figure 4 is a section on line 4—4 of Figure 3, looking in the direction of the arrows;

Figure 5 is a section on line 5—5 of Figure 3, looking in the direction of the arrows;

Figure 6 is a detail of the flint receptacle;

Figure 7 is a detail elevation of the sparking mechanism; on line 7—7 of Figure 3.

Figures 4, 5, 6 and 7 are on an enlarged scale.

Flint sparking cigar lighters are old and have been made in many forms. All depend for their usefulness upon a small piece of flint or other suitable material, pressed against the face of an abrasive cutting wheel, the rapid movement of which removes minute particles of the flint, with the generation of heat sufficient to raise the particles to an incandescent heat, throwing them in a shower in the direction of rotation of the abrading tool.

The main body part of my device, upon which all the other elements are grouped, is a reservoir 1, within which the liquid fuel is contained, preferably also cotton or other absorbent material is introduced, in order to take up and hold the alcohol or gasoline fuel. An aperture is formed in the bottom 11 of this reservoir through which the fuel may be introduced as required and this aperture is closed by a screw-plug 2, formed from solid stock, and having a projecting hollow tang 21 within which may be stored flints 3. Tang 21 is closed by a friction plug 22, which forms a tight fit with the interior of tang 21.

Upon the top 12 of the reservoir is mounted the sparking mechanism, made up of a standard 4 mounted perpendicularly to the surface of the top 12 and carrying transversely to its upper end a flint tube 41, hav-

ing at one end an interior screw threaded section, 42, and at the other a cover 43, having an opening upon one side (see Fig. 7). Within the flint tube is mounted a spiral spring 44 and in the threaded section 42 is a screw 45, which may be turned to give any desired tension to the spring.

Mounted upon the top 12, in line with the flint tube 41 is a perpendicular shaft 5, its lower end having a bearing in a recess in the surface of top 12 and its upper end a bearing in the top of cover 43. Upon this shaft 5 are mounted two wheels, one, 51, being a thumb wheel, preferably with a milled or knurled edge and the other 52, somewhat less in diameter, having a file cutting-edge, and lying within and substantially covered by the cover 43, and directly opposite the end of tube 41. The cover is cut away opposite the end of tube 41 and the opening continues at the side opposite the wick tube, as shown in Figure 7. Between the end of spring 44 and spark wheel 52 is placed a flint 3 which is kept by the spring pressed against the file periphery of the spark wheel.

In Figure 4 most clearly appear the flame elements, which are in a line parallel to the flint tube (see Figs. 3 and 4). Upon the top 12 of the reservoir is mounted a standard 6, having a central axial opening from top to bottom, communicating with the interior of the reservoir 1. The upper end of the standard or wick tube 6, is formed with a conical seat 61 and within the tube is carried a lamp wick 62. Opposite the end 42 of the flint tube is a hollow standard 7, having upstanding ears 71 provided with bearing apertures for the pintle 81 of a swinging arm 8. Within the hollow standard 7 is a plunger 72, spring pressed by a spring 73. The rear end of arm 8 is formed with two flat surfaces 82 which when it is perpendicular to or parallel with the top 12 are engaged by the plunger 72, yieldingly holding the arm 8 in one position or the other but preventing it from remaining at any intermediate position. Upon the free end of arm 8 is a head 83 having a hollow 84 the outer edges of which are adapted to engage the conical seat 61 of the wick tube 6 with a line engagement (see Fig. 4) and hermetically close the open end of the wick tube, to prevent leakage or evaporation of the

fuel, when the device is not in use. Such a line engagement requires no force to form and is perfectly efficient.

The operation is as follows: the reservoir 5 being filled with suitable volatile fluid, the wick will draw up a supply to the open end of the wick tube. When it is desired to produce a flame the arm 8 is lifted, against the resistance of spring 73 until a flat 81 is 10 parallel with the face of plunger 72 when the arm will be held in upright position, the end of the wick 62 being exposed. A sharp turn of shaft 5 by means of the thumb wheel 51 will cause spark wheel 52 to cut a myriad 15 of incandescent particles off the flint 3, pressed against its face and throw them through the side opening in cover 43, directly upon the end of wick 3, igniting the vaporized fuel. When it is desired to 20 quench the flame the arm 8 is swung upon its pintle 81, at first resisted by the spring 73 and later urged by spring 73, as the corner between the two flat surfaces 82 is 25 passed. The head 83 will be pressed against the conical seat 61 effectually closing the wick tube and covering the wick. It will be observed that the actuation of the spark wheel 52 without direct application of power is made possible by the use of a shaft for the 30 spark wheel and an actuation wheel for the shaft, with the necessary bearings at both ends of the shaft. The opening and closing

of the wick tube is rendered semi-automatic and secure against leakage or evaporation. The filling of the device and the storage of 35 spare flints is also conveniently provided for and the renewing and use of the flint in active use is made cleanly and easy, without any necessity, in the operation of the device for the hands to come in contact either with 40 the wick or spark wheel, and with provision for the covering of these parts at all times, so that neither the hands nor the clothing may be soiled.

I claim:—

In a cigar lighter, in combination, a fuel reservoir; a standard perpendicular to the upper end of the reservoir; a flint tube carried by the standard across its upper end; a spring within the flint tube; an abutment at 50 one end of the flint tube; a cover at the other end; a shaft perpendicular to the upper end of the reservoir, journalled at one end in the top of the reservoir and at the other end in the flint tube cover; a spark wheel fast to the shaft, within the cover and opposite the end of the flint tube; a thumb wheel on the shaft; a wick tube to one side of the flint tube cover; its upper end opposite the spark 55 wheel.

Signed at Boston, Massachusetts, this twenty-second day of March, 1926.

EDWARD FOSTER CLARK.
